UNITED STATES PATENT OFFICE.

JOHN R. CARTER, OF AUGUSTA, KENTUCKY, AND JOSEPH E. HAUSFELD, OF CINCINNATI, OHIO, ASSIGNORS TO ERNST H. HUENEFELD, OF CINCINNATI, OHIO.

DESIGN FOR A WARMING-OVEN.

SPECIFICATION forming part of Design No. 33,799, dated December 25, 1900.

Application filed December 3, 1900. Serial No. 38,563. Term of patent 14 years.

To all whom it may concern:

Be it known that we, JOHN R. CARTER, residing at Augusta, in the county of Bracken and State of Kentucky, and JOSEPH E. HAUSFELD, residing at Cincinnati, in the county of Hamilton and State of Ohio, citizens of the United States, have invented and produced a new and original Design for a Warming-Oven, of which the following is a specification, reference being had to the accompanying drawings, forming a part thereof.

In the accompanying drawings, Figure 1 is a perspective view, and Fig. 2 is an end view.

The leading feature of our design for a warming-oven consists of an approximately rectangular body, having a roll or swell door at the front thereof and the front of the ends of the body curved to conform to the contour of the door, and ornamental surfaces in relief on the ends of the body and door, each having configuration to coact or coöperate with the other to form a complete design.

1 represents the approximately rectangular body, having the roll or swell door 2 at the

front thereof and having open-work brackets 3 beneath the ends thereof. The brackets 3 comprise straight rear members 4, top and bottom portions 5 and 6, respectively, extending at right angles from the same and parallel with each other, and a front member 7, having a rolled front edge and curved inward in the arc of a circle between its ends, and an approximately horizontal portion 8 connects the inwardly-curved portion of the front member 7 and the rear member 4.

Ornamental plates 9 and 10 are located at the ends of the door 2 and the forward ends of the end portions of the body 1, respectively, and the ornamented surfaces thereof coact or coöperate to form a complete design.

What we claim is—

The design for a warming-oven shown and described.

JOHN R. CARTER.
JOSEPH E. HAUSFELD.
